Inventor

UNITED STATES PATENT OFFICE.

HENRY NEFF, OF NEW WASHINGTON, PENNSYLVANIA.

DESIGN FOR A NAIL-SET.

SPECIFICATION forming part of Design No. 25,308, dated March 31, 1896.

Application filed February 29, 1896. Serial No. 581,397. Term of patent 14 years.

To all whom it may concern:

Be it known that I, HENRY NEFF, a citizen of the United States, residing at New Washington, in the county of Clearfield and State 5 of Pennsylvania, have invented a new and original Design for Nail-Sets, of which the following is a specification.

This invention relates to a new and original design for nail-sets, and it has for its object 10 to provide a design of this character that shall be both useful and ornamental.

The leading feature of the design resides in a straight shank provided with a symmetrical taper at one end; at its opposite end with an 15 annular enlargement having a convexed top face; adjacent to said annular enlargement with a lateral projection peripherally and annularly concaved to form substantially an hour-glass-shaped figure, and diametrically 20 opposite said peripherally and annularly concaved projection with a conically-shaped projection.

In the drawings, Figure 1 is a perspective view of a nail-set embodying the herein-described design. Fig. 2 is a plan view thereof. 25

Referring to the accompanying drawings, the numeral 1 designates a straight shank symmetrically tapered at one end, as at 2, and provided at its opposite end with an annular enlargement 3 having a convex top face 4. 30 Adjacent to the enlargement 3 the shank 1 is provided with a lateral projection 5, which is peripherally and annularly concaved, as at 6, to form substantially an hour-glass-shaped figure, and diametrically opposite the projection 5 the shank 1 is further provided with a conically-shaped projection 7, which completes the design.

What I claim is—

The design for a nail-set herein shown and 40 described.

In testimony that I claim the foregoing as my own I have hereto affixed my signature in the presence of two witnesses.

HENRY NEFF.
